Patented July 13, 1976

240,479

SEAT OR SIMILAR ARTICLE

Matti Halme, Helsinki, Finland, assignor to
Burris Industries, Inc., Lincolnton, N.C.

Filed Feb. 13, 1975, Ser. No. 549,520

Term of patent 14 years

Int. Cl. D6—01

U.S. Cl. D6—37

Fig. 2

Fig. 1

Fig. 3

Fig. 4

FIG. 5

FIG. 6

FIG. 7

FIG. 8

FIG. 1 is a front perspective view of a seat showing my design in the form of an armchair;

FIG. 2 is a side elevational view thereof but on a smaller scale;

FIG. 3 is a rear elevational view thereof also on a smaller scale;

FIG. 4 is a front elevational view thereof also on a smaller scale;

FIG. 5 is a front elevational view of a seat showing my design in the form of a sofa;

FIG. 6 is a top plan view of the seat of FIG. 5 on a smaller scale;

FIG. 7 is a rear elevational view of the seat of FIG. 5 also on a smaller scale; and

FIG. 8 is a side elevational view of the seat of FIG. 5 also on a smaller scale.

I claim:

The ornamental design for a seat or similar article, substantially as shown.
